CLAIM

I claim, the ornamental design for a packaging pouch for facial mask pack, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a packaging pouch for facial mask pack, showing my new design;

FIG. 2 is a rear view with thereof;

FIG. 3 is a front view of a second embodiment of the packaging pouch for facial mask pack; and,

FIG. 4 is a rear view thereof.

The right side, left side, top, and bottom views are omitted as the packaging pouch for facial mask pack has negligible width.
